CLAIM

The ornamental design for a 1x4 distribution point unit, as shown and described.

DESCRIPTION

This Application claims priority to U.S. Utility Patent application Ser. No. 15/223,329, filed on Jul. 29, 2016, which is incorporated-by-reference herein in its entirety.

FIG. 1 is a front perspective view of a 1x4 distribution point unit showing our new design;

FIG. 2 is a bottom view thereof;

FIG. 3 is a top view thereof;

FIG. 4 is a right view thereof;

FIG. 5 is a left view thereof;

FIG. 6 is a front view thereof; and,

FIG. 7 is a rear view thereof.

The broken lines immediately adjacent to the claim represent the bounds of the claimed design, while all other broken lines are directed to environment; the broken lines form no part of the claimed design.
